UNITED STATES PATENT OFFICE

94,610

DESIGN FOR A BURNER CAP

Stanley H. Hobson, Rockford, Ill., assignor to
Geo. D. Roper Corporation, Rockford, Ill., a
corporation of Illinois

Application April 20, 1934, Serial No. 51,464

Term of patent 7 years

To all whom it may concern:

Be it known that I, Stanley H. Hobson, a citizen of the United States, residing at Rockford, in the county of Winnebago and State of Illinois, have invented a new, original, and ornamental Design for a Burner Cap, of which the following is a specification, reference being had to the accompanying drawing, forming part thereof.

In the drawing:

Figure 1 is a perspective of a gas burner cap showing my new design, and

Figs. 2 and 3 are side and plan views, respectively.

I claim:

The ornamental design for a burner cap substantially as shown.

STANLEY H. HOBSON.
